UNITED STATES PATENT OFFICE.

THOMAS CAMPBELL, OF IRWIN, PENNSYLVANIA.

DESIGN FOR A BELT-HOLDER.

SPECIFICATION forming part of Design No. 35,751, dated February 18, 1902.

Application filed January 6, 1902. Serial No. 88,703. Term of patent 7 years.

To all whom it may concern:

Be it known that I, THOMAS CAMPBELL, a citizen of the United States, residing at Irwin, in the county of Westmoreland and State of Pennsylvania, have invented and produced a certain new and original Design for a Belt-Holder; and I do declare the following to be a full, clear, and exact description of the invention, such as will enable others skilled in the art to which it appertains to make and use the same.

The invention relates to a new and original design for a belt-holder; and it consists of the design of the configuration shown in the accompanying drawings, in which—

Figure 1 is a front perspective view, and Fig. 2 is a rear view.

The leading feature of the design consists of the cross-shaped plate 1, from the vertical

members 2 of which projects a curved bow 3 and from the rear side of which projects a fastening device 4. In use the fastening device is adapted to be engaged with a waistband of a skirt or of a pair of trousers, and a belt is adapted to be threaded through the bow 3, in which position it will be prevented from riding over the edge of the waistband.

What I claim is—

The design for a belt-holder, as herein shown and described.

In testimony whereof I have hereunto set my hand in presence of two subscribing witnesses.

TOM CAMPBELL.
